UNITED STATES PATENT OFFICE.

ALTHEOD J. HOULE, OF MANCHESTER, NEW HAMPSHIRE.

DESIGN FOR A BELT-BUCKLE MEMBER.

SPECIFICATION forming part of Design No. 36,165, dated December 9, 1902.

Application filed August 15, 1902. Serial No. 119,823. Term of patent 34 years.

To all whom it may concern:

Be it known that I, ALTHEOD J. HOULE, a citizen of the United States, residing at Manchester, in the county of Hillsboro and State 5 of New Hampshire, have invented and produced a new, original, and ornamental Design for a Belt-Buckle Member, of which the following is a specification, reference being had to the accompanying drawing.

10 The drawing represents in plan a belt-buckle member illustrating my new design.

The leading or material feature of my design for a belt-buckle member consists in the open heart-shaped body portion having a 15 transversely-slotted base.

The buckle member A is shown as having a slotted base a and an open portion of heart-

shaped contour a' thereon, the apex a^2 of the lobes being slightly raised above the plane of the other parts of said member A.

Having fully described my design, what I claim, and desire to secure by Letters Patent, is—

The ornamental design for a belt-buckle member, substantially as herein shown and 25 described.

In testimony whereof I have signed my name to this specification in the presence of two subscribing witnesses.

ALTHEOD J. HOULE.
